(57) **CLAIM**

The ornamental design for a portion of a storage bin, as shown and described.

DESCRIPTION

FIG. 1 is a top front exploded perspective view of a storage bin, showing my new design.

FIG. 2 is a bottom rear exploded perspective view of the storage bin.

FIG. 3 is a top front perspective view of the storage bin.

FIG. 4 is a front elevational exploded view of the storage bin.

FIG. 5 is a rear elevational exploded view of the storage bin.

FIG. 6 is a right side elevational exploded view of the storage bin.

FIG. 7 is a left side elevational exploded view of the storage bin.

FIG. 8 is a top plan view of the storage bin.

FIG. 9 is a bottom plan view of the storage bin.

FIG. 10 is a close-up view of the detail area indicated in FIG. 1.

FIG. 11 is a close-up view the detail area indicated in FIG. 2.

FIG. 12 is a partial sectional view, taken along section 12-12 indicated in FIG. 4; and,

FIG. 13 is a partial sectional view, taken along section 13-13 indicated in FIG. 4.

Features shown in broken lines are for the purpose of illustrating possible environment, and form no part of the claimed invention. The long-dash-double-short-dash lines are for the purpose of indicating a boundary for the claimed design.

1 Claim, 12 Drawing Sheets
